(57) **CLAIM**

The ornamental design for a food warming mat as shown and described.

DESCRIPTION

FIG. 1 is a top perspective view of a food warming mat showing my new design;

FIG. 2 is a rear perspective view thereof;

FIG. 3 is a front elevational view thereof;

FIG. 4 is a rear elevational view thereof;

FIG. 5 is a left view thereof;

FIG. 6 is a right view thereof;

FIG. 7 is a top plan view thereof;

FIG. 8 is a bottom plan view thereof; and,

FIG. 9 is another perspective view thereof, showing the food warming mat in a folded configuration.

The evenly broken lines illustrate portions of the food warming mat that form no part of the claimed design.

1 Claim, 9 Drawing Sheets
